Primary Examiner — Omeed Agilee(74) *Attorney, Agent, or Firm* — Frost Brown Todd LLC**CLAIM**

The ornamental design for an examination table, as shown and described.

DESCRIPTION

FIG. 1 is a front perspective view of an examination table showing our new design in a raised state;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is a front perspective view of the examination table showing our new design in a lowered state;
 FIG. 10 is a rear perspective view thereof;
 FIG. 11 is a front elevational view thereof;
 FIG. 12 is a rear elevational view thereof;
 FIG. 13 is a left side elevational view thereof;
 FIG. 14 is a right side elevational view thereof;
 FIG. 15 is a top plan view thereof; and,
 FIG. 16 is a bottom plan view thereof.

The broken lines depict portions of the examination table that form no part of the claimed design.
